(57) **CLAIM**

The ornamental design for a “spring clip with magnetic base,” as shown and described.

DESCRIPTION

FIG. 1 is a front elevational view of a “spring clip with magnetic base” showing my new design; FIG. 2 is a right elevational view, the left being the mirror image thereof;

FIG. 3 is a bottom plan view thereof;

FIG. 4 is a top plan view thereof;

FIG. 5 is a rear elevational view thereof; and,

FIG. 6 is a rear perspective view thereof.
